CLARENCE J. RODMAN, OF WILKINSBURG, PENNSYLVANIA, ASSIGNOR TO WESTINGHOUSE ELECTRIC & MANUFACTURING COMPANY, A CORPORATION OF PENNSYLVANIA

ELIMINATION OF IMPURITIES IN INSULATING OILS

Application filed October 21, 1924. Serial No. 745,042.

My invention relates to oil-immersed electrical devices and particularly to means for eliminating the impurities in the oil used in such devices.

5 One object of my invention is to provide an oil-insulated electrical translating device having means for causing an inert gas to bubble through the insulating oil for purifying it.

Another object of my invention is to provide 10 an oil-immersed electrical translating device that shall have a small amount of inert gas gently bubbling through the insulating oil for the purpose of purifying it.

A further object of my invention is to provide 15 an oil-insulated electrical translating device having means for continually purifying the insulating oil.

In oil-immersed electrical devices, such as circuit interrupters and transformers, the dielectric strength of the insulating oil gradually decreases by reason of the accumulation 20 of impurities, such as water, carbon and oil sludge, or other decomposition products. The accumulation of such undesirable ingredients 25 in the insulating oil varies with the normal operating temperature of the translating device, together with the surface area that is exposed to the atmosphere and many other conditions, the origin of some of which has

30 not been definitely determined. I have found that, by bubbling an inert gas, such as dry carbon dioxide, or nitrogen, through the insulating oil, it is possible to remove a large percentage of the water; sweep 35 out any highly volatile solvents and coagulate or agglomerate many of the finely divided bodies, such as carbon or resins.

The single figure of the accompanying drawings is a view, partially in elevation and 40 partially in section, of a transformer embodying my invention.

My invention comprises, in general, an electrical translating device 1 containing windings 2 of a transformer and a body of insulating fluid 3, such as petroleum oil, as well understood in the art, surrounding the windings 2, together with a pipe network 4 for liberating gas near the bottom of the translating device 1 in such manner that the liber-

ated gas rises upwardly or bubbles through the insulating oil 3, thereby purifying it.

The network 4 is preferably so disposed that the gas is liberated near the walls of the electrical translating device 1 in order to 55 avoid any tendency for the accumulation of bodies of gas within the windings 2, thereby displacing the insulating oil 3. Apertures 5 in the network 4 should be sufficiently small in diameter to limit the escaping gas bubbles 60 to a volume insufficient to cause excessive bubbling at the upper surface of the insulating fluid 3.

A container 6 that is filled with compressed carbon dioxide, nitrogen, or mixtures of such 65 gases, supplies gas to the network 4 through a regulating valve 7 to a dehydrator 8 that, in turn, is connected to a telltale 9 in a pipe line 11. The telltale 9 contains a suitable liquid for the purpose of giving a visual indication 70 of the flow of gas from the container 6 to the electrical translating device 1. A suitable breathing regulator 12 is provided for the translating device 1.

The pipe line 11 is preferably provided 75 with a suitable check valve 13 in order to prevent oil from being forced back into the telltale 9 and dehydrator 8 and regulating valve 7. The insulating oil 3 in the translating device should not contain over one-thous- 80 andth part of one percent of water, whereas ordinary commercial carbon dioxide contains about two-hundredths of one percent of water. Accordingly, it is necessary to provide the system with the dehydrator 8. 85

In operating an electrical translating device according to my invention, a cylinder of gas weighing about fifty pounds is connected to the regulating valve 7 that is adjusted to liberate approximately 20 cu. centimeters of 90 gas per minute. Under these conditions, the tank needs to be replaced about once per year. However, the amount of gas liberated in the translating device must be varied in accordance with the working conditions and the 95 cubic capacity of the particular device. The gas, in passing upwardly through the insulating oil 3, takes up a percentage of the water found therein as well as certain of the volatile solvents. At the same time, the gas 100

coagulates or agglomerates certain of the more finely divided bodies, such as carbon or resin, and deposits them as a precipitate, thereby improving the dielectric qualities of the oil and continually purifying such oil by preventing the accumulation and assisting in the disintegration of the impurities commonly termed oil sludges.

An electrical translating device containing oil-purifying apparatus embodying my invention materially prolongs the life of the insulating medium and sustains its dielectric strength by the process of causing a dry, inert, or practically oxygen-free, gas to bubble therethrough. The bubbling gas serves to remove water, precipitate the sludge, and to prevent the formation of other products of decomposition of oil incidental to the operation of oil-immersed electrical translating devices. I do not wish to be restricted to the specific arrangement of parts herein set forth, as various modifications thereof may be effected without departing from the spirit and scope of my invention. I desire therefore that only such limitations shall be imposed as are indicated in the appended claims.

In the appended claims, the expression "inert gas" shall be understood as comprehending a gas from which oxygen has been or is largely or substantially excluded.

I claim as my invention:

1. In the art of purifying the insulating oil of an electrical translating device, the step which consists in passing an inert gas into coating relation with said medium to preserve its dielectric characteristics.

2. In the art of purifying the insulating oil of an electrical translating device, the step which consists in bubbling an inert gas through said oil to preserve its dielectric characteristics.

3. In the art of purifying the insulating oil of an electrical translating device, the step which consists in bubbling dry carbon-dioxide gas through said oil to preserve its dielectric characteristics.

4. In the art of dehydrating the insulating oil of an electrical device, the step which consists in bubbling a dehydrated inert gas through said oil to preserve its dielectric characteristics.

5. In the art of dehydrating the insulating oil of an electrical device, the step which consists in bubbling dry carbon-dioxide gas through said oil to preserve its dielectric characteristics.

In testimony whereof, I have hereunto subscribed my name this 14th day of October, 1924.

CLARENCE J. RODMAN.
